UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A MISS'S WALKING-SKIRT.

SPECIFICATION forming part of Design No. 14,825, dated February 26, 1884.

Application filed January 23, 1884. Term of patent 23 years.

To all whom it may concern:

Be it known that I, SARAH JANE SHIELS, of the city, county, and State of New York, have invented and produced a new and original Design for a Pattern of a Miss's Walking-Skirt, (numbered 9,045;) and I do hereby declare that the engraved prints accompanying this specification convey to any one accustomed to using paper patterns a clear understanding of how a garment made up by the pattern will appear.

The design shows a round skirt with a drapery upon the front extending from the belt to the lower edge, and displaying plaits

turning toward the center; plain panels at the sides exhibiting pointed strap-extensions at their front edges; and a deep full back drapery displaying drapery-plaits in its front edges, and loopings at the center.

What I claim as my invention, and desire to secure by Letters Patent, is—

The design for a miss's walking-skirt, as shown in the engraved prints accompanying this specification.

SARAH JANE SHIELS.
